LOOM REED

Virgle Franklin McLane and Samuel Fuller
 McLane, Gaffney, S. C., assignors to Southern
 Loom Reed Manufacturing Company, Inc.,
 Gaffney, S. C., a corporation of South Carolina

Application March 26, 1945, Serial No. 584,922

4 Claims. (Cl. 139—192)

This invention relates to a loom reed, and more especially to a reed known as the cotton type, wherein a pair of half rounds or wooden members are used at top and bottom of the reed for holding the splits in spaced relation to each other to form spaces therebetween through which the warp passes in a weaving operation. These loom reeds have heretofore been made in a conventional manner with a pair of half round members disposed near each end of the splits and a spirally wound cord passing around the half round members and between the splits to hold them in spaced relation. These half round members have heretofore had secured between the ends thereof, and extending from the end of one set of half round members to the ends of the other set of half round members a pair of end bars to complete the frame and lend rigidity thereto. These end bars have usually stopped flush with the outer edges of the half round members and a suitable metallic cap has been inserted over the ends of the half round members and over the ends of the end bars and secured in position by a pair of tacks driven through suitable holes in the metal caps and embedded in the half round members. It has often happened that these circular metal caps or ferrules, being driven over the ends of the half round members, would engage the ends of the splits and bend them over and result in the springing of the splits and thus making an imperfect loom reed.

It is an object of this invention to eliminate this trouble by providing the end bars so that they have substantially greater thickness than the conventional end bars and yet one side of the end bars lies flush with the edges of the splits on the side of the loom reed past which the shuttle passes in a weaving operation. However, this greatly increased thickness causes the end bars to project outwardly on the other side of the splits and since the end bars are of conventional thickness where they are disposed between the half round members, this results in a shoulder being formed near each end of the end bars which fits snugly against the metallic ferrule fastened on the ends of the end bars. These end bars also project outwardly past the half round members and the metallic ferrules have instead of one notch, two notches to fit past the ends of the end bars and thus no portion of the metallic ferrules engages the splits to cause any springing action of the same.

It is therefore an object of this invention to provide a loom reed having half round members

5 for holding the splits in position with end bars projecting through and extending beyond the outer edges of the half round members, said end bars having shoulders thereon to fit against the proximate edges of the half round members, and metallic ferrules fitted and fastened over the ends of the half round members, and each ferrule having a pair of opposed slots therein for fitting past the two portions of the end bars over which it is secured in being positioned on the ends of the half round members.

10 It is another object of this invention to provide a loom reed in which the end bars extend beyond the outer edges of the half rounds so as to be engaged by the reed cap of the lay of the loom and thus firmly support the reed in the lay of the loom and thus relieve any pressure being exerted by the reed cap in the lay of the loom on the ends of the splits projecting outwardly from the outer edges of the half rounds of the reed.

15 Some of the objects of the invention having been stated, other objects will appear as the description proceeds when taken in connection with the accompanying drawing in which:

20 Figure 1 is a side elevation of a loom reed with the central portion thereof broken away and showing the invention;

25 Figure 2 is an end view of Figure 1 looking from the right hand end of Figure 1;

30 Figure 3 is a vertical sectional view taken along the line 3—3 of Figure 1 and being on an enlarged scale;

35 Figure 4 is a top plan view of one of the metallic ferrules;

40 Figure 5 is an end view of Figure 4 looking from along the line 5—5 in Figure 4;

45 Figure 6 is a vertical sectional view taken along the line 6—6 in Figure 5;

50 Figure 7 is a sectional view taken on an enlarged scale along the line 7—7 in Figure 1.

Referring more specifically to the drawing, numerals 10 and 11 indicate the half round members, and as both upper and lower portions of the 55 reed are identical, like reference characters will apply. These half round members are fitted on opposed edges of splits 12 and a pitched cord 13 is spirally wound around the half round members to securely bind the half round members to the edges of the splits and also to space the splits from each other to form spaces therebetween through which the warp yarn of the loom passes in a weaving operation. Between the ends of the half round members are secured end bars 16 and these end bars are of increased thickness, from

the conventional end bars. The portion 17 which lies between the half round members is of the same width as the width of the splits, whereas the central portion of the end bars 16 are of about twice the thickness of the portions which lie between the half round members. This provides a shoulder 19 near each end of the end bars 16. I then take a conventional cap or ferraule 20, and in view of the fact that the ends 17 of the end bars 16 extend substantially the same distance past the outer edges of the half round members as the splits extend, the ferrules not only have conventional notch 23 therein, but also an additional notch 24 in the outer portion thereof which fits around the outer portion of the end 17 of the end bars. A pair of conventional tacks 25 are employed for nailing the same through suitable holes 26 in ends of the cap members 20 and into the half round members 10 and 11 to secure the caps 20 in position over the end bars. The periphery of these caps 20 fits snugly against the shoulders 19 of the end bars. This provides a very substantial frame in that the shoulders 19 serve to hold the loom reed frame in rectangular position and at the same time, due to the fact that there is no chance whatever of the caps 20 fitting against the ends of the splits 12, no springing of the splits can take place and thus a perfect loom reed can be manufactured by the use of these improvements.

In a conventional loom there is a lower groove in the lay for receiving the ends of the splits 12 and a reed cap having a groove into which the upper ends of the splits 12 fit. This holds the reed in the loom and on the beat-up especially, there is a good bit of lateral strain on the ends of the splits projecting beyond the half rounds 10 and 11. By having the end bars 16 provided with projecting portions 17 extending beyond the outer edges of the half rounds to substantially the same, or slightly greater distance than the splits, these portions 17 of the end bars, being much more rigid than the splits, withstand this lateral pressure exerted on the reed in a beat-up operation and thus eliminates any possibility of lateral strain on the ends of the splits tending to warp the splits.

In the drawing and specification, there has been set forth a preferred embodiment of the invention, and although specific terms are employed, they are used in a generic and descriptive sense only, and not for purposes of limitation, the scope of the invention being defined in the claims.

We claim:

1. A loom reed formed from splits held in spaced relation to each other by half round wooden members on each edge of the splits near each end thereof, and having a pitched cord wound spirally around the half round members and passing between the splits to space the splits from each other, end bars disposed between the half round members near the ends thereof, and whose ends project outwardly beyond the outer edges of the half round members, metallic caps each having a pair of slots therein and fitting over the ends of the half round members and receiving the end portions of the end bars in said slots, each end bar having shoulder on one side thereof adjacent the metallic caps for fitting against the proximate surfaces of the metallic caps.
2. A loom reed having splits and a pair of half round members fitting against the edges of the splits, a pair of end bars having their ends fitting between the ends of the half round members and provided with shoulders adjacent the proximate surfaces of two pairs of half round members, and metallic caps each having a pair of slots therein for fitting over the ends of the half round members and receiving the end bars within said slots.
3. A cotton loom reed having a rib formed from a pair of half round members engaging opposed edges of a plurality of splits, an end bar disposed between the ends of the half round members and having a shoulder adjacent the inner edge of one of the half round members, and a cap having a pair of slots therein for fitting over the ends of the half round members and on each side of the end bar.
4. A cotton loom reed having ribs formed from pairs of half round members engaging opposed edges of a plurality of splits near their ends, end bars disposed between the ends of the half round members and each having a shoulder adjacent the inner edge of the half round members, the half round members having a cap inserted thereover, and having slots therein fitting on each side of the end bars, the shoulders on the ends bars fitting against the exterior of said caps, the end bars projecting outwardly beyond the outer edges of the half round members to a point substantially flush with the ends of the splits, said projecting portions of the end bars being adapted to occupy a position in suitable grooves in the lay of the loom for supporting the reed in the lay of the loom.
